(57) **CLAIM**

The ornamental design for audio video shelving unit, as shown and described.

DESCRIPTION

FIG. 1 is a front perspective view of a first embodiment of the audio video shelving unit;

FIG. 2 is a front elevational view thereof;

FIG. 3 is a rear elevational view thereof;

FIG. 4 is a top plan view thereof;

FIG. 5 is a right side view thereof (the left side being a mirror image of the right side view);

FIG. 6 is a front perspective view of a second embodiment of the audio video shelving unit; and,

FIG. 7 is a top plan view of the embodiment shown in FIG. 6 (all other views of the second embodiment having the same appearance as FIGS. 1-5).

The broken lines are for environmental purposes only and form no part of the claimed design.

The “pattern” that can be seen on the rear panel between the two vertical posts is only shown on a portion of this area but understood to cover the whole surface.
